(57) **ABSTRACT**

An electronic door latch includes a sensor mounted inside of an outer surface of the door. The sensor may be a proximity sensor, a touch sensor or other suitable sensor configured to determine if a user's hand is present. The door latch release system further includes a powered latch that selectively retains the door latch in a closed position. The system may include a handle formed by a flange or other structure extending across a portion of a recess or pocket in the door. The system may include a receiver that utilizes a signal from a security transmitter (e.g. keyless entry fob).

FIG. 2

FIG. 4

FIG. 8

FIG. 9

FLUSH-MOUNTED DOOR HANDLE FOR VEHICLES

CROSS REFERENCE TO RELATED APPLICATION

This application claims the benefit of U.S. Provisional Application No. 61/666,493, filed Jun. 29, 2012, entitled, FLUSH MOUNTED DOOR HANDLE FOR VEHICLES, the entire contents of which are incorporated herein by reference.

FIELD OF THE INVENTION

The present invention relates to flush-mounted door handles for vehicles that may utilize a powered latch.

BACKGROUND OF THE INVENTION

Vehicle door handles typically protrude from the door, and interfere with vehicle styling and/or aerodynamics. Various outside door handles such as paddle type handles, pull-strap handles, push-button activated handles, and the like have been developed. However, known conventional door handles may suffer from various drawbacks.

SUMMARY OF THE INVENTION

One aspect of the present invention is a flush-mounted door handle that is operably interconnected with an electronic door latch release for motor vehicles of the type having a door with a door structure and an outer surface and/or keyless entry feature and/or a styled ("Class A") outer surface portion. The handle outer surface is defined by the styled surface of the vehicle, and may comprise a portion of the substantially continuous portion of the styled outer surface. The handle is flush to the door frame outer surface which is covered with a Decorative Class part known as the appliqué. A sensor is mounted to the door at a location adjacent the portion of the outer surface defining a surface contour. The sensor is selected from the group consisting of proximity sensors or touch sensors. The release system may also include a visual indicator on the door that is configured to convey the general location of the sensor to a user. The visual indicator may comprise a light, a marking or the like on the surface of the door, a recessed pocket, or other indicia or irregularity on the outer side of the door. The door latch release system further includes a powered latch that retains the door in a closed position when the latch is in an engaged configuration, and permits opening of the door when the latch is in a release configuration. The powered latch shifts from the engaged configuration to the release configuration if the sensor generates a predefined signal indicating that a user has actuated the sensor/switch. The system may include a handle formed by a recess in an outer side or surface of the door. A flange or other structure extends across a portion of the recess to form a pocket that provides an inwardly-facing grip surface that allows a user to pull the door open without movement of the handle relative to the vehicle door. The system may include a receiver also known as door control unit (DCU) that utilizes a signal from a security transmitter (e.g. keyless entry fob). The system may include a proximity (e.g. capacitive) or a touch sensitive pad (e.g. piezoelectric or other pressure/force detection sensor) that is operably connected to the sensor, and is actuated when a user touches the sensor or other surface. The system may comprise a handle located above the door belt line in a vertically

extending portion of a door frame adjacent to a window of the door. The handle may comprise a vertically elongated opening, recess or depression into the door having a surface that faces outwardly. The system may also include a touch keypad with numbers that are normally hidden, but illuminate when the hidden keypad is touched. The keypad may be utilized to enter security codes or the like.

These and other aspects, objects, and features of the present invention will be understood and appreciated by those skilled in the art upon studying the following specification, claims, and appended drawings.

BRIEF DESCRIPTION OF THE DRAWINGS

In the drawings:

FIG. 1 is a side elevational view of a motor vehicle incorporating a flush door handle according to one aspect of the present invention;

FIG. 2 is a fragmentary, enlarged view of a portion of the vehicle door of FIG. 1;

FIG. 3 is a cross-sectional view of a first version of the door assembly of FIG. 2 taken along the line III-III; FIG. 2;

FIG. 4 is a cross sectional view of a second version of the door handle of FIG. 3;

FIG. 5 is an exploded isometric view of a cover and housing for a piezoelectric or capacitive sensor version of the handle of FIG. 1;

FIG. 6 is a partially fragmentary schematic front view of a keyless entry subassembly incorporating a piezoelectric or capacitive sensor;

FIG. 7 is an edge view of the keyless entry subassembly of FIG. 6;

FIG. 8 is a partially fragmentary view of a flush-mounted door handle according to another aspect of the present invention; and

FIG. 9 is a cross sectional view of the door handle of FIG. 8 taken along the line IX-IX; FIG. 8.

DETAILED DESCRIPTION OF THE PREFERRED EMBODIMENTS

For purposes of description herein, the terms "upper," "lower," "right," "left," "rear," "front," "vertical," "horizontal," and derivatives thereof shall relate to the invention as oriented in FIG. 1. However, it is to be understood that the invention may assume various alternative orientations, except where expressly specified to the contrary. It is also to be understood that the specific devices and processes illustrated in the attached drawing, and described in the following specifications are simply exemplary embodiments of the inventive concepts defined in the appended claims. Hence, specific dimensions and other physical characteristics relating to the embodiments disclosed herein are not to be considered as limiting, unless the claims expressly state otherwise.

With reference to FIG. 1, a motor vehicle 1 includes front and rear doors 2 and 3, respectively, and a flush-mounted handle assembly 10 that requires no moving parts to be manually actuated by a user. It will be understood that the vehicle also includes front and rear doors on the passenger side that are substantially identical to the doors 2 and 3 shown in FIG. 1. The door 2 includes a beltway 3, a window 4 above the beltway, and a lower surface 5 below the beltway. The door 2 also includes a door frame 6 having a portion 7 having an outer surface 8. The door also includes a handle assembly 10 having a styled or "Class A" outer surface 11 that is substantially flush to the outer surface 8 of

door frame 6. The handle 10 is fixed (i.e. does not move or have any moving parts) and is preferably flush to the door outer surface 8. Handle assembly 10 may also include an inwardly-extending depression and/or an outwardly-facing projection 12A forming a pocket 12 that is configured to receive a user's fingers whereby the user can grasp the handle 10 and pull the door 2 to an open position upon release of the door latch.

With further reference to FIGS. 2 and 3, handle assembly 10 may include a touchpad 20 and a sensor symbol or indicia 15 that may operably connected to powered latch 16 (FIG. 1). Powered latch 16 may be substantially the same as the latches disclosed in U.S. patent application Ser. No. 12/402,744 entitled "Universal Global Latch System" (U.S. Patent Publication No. 2010/0235057), now U.S. Pat. No. 8,746,755 and/or U.S. patent application Ser. No. 12/402,792 entitled "Universal Global Latch System" (U.S. Patent Publication No. 2010/0235059), now U.S. Pat. No. 8,544,901 and/or the side door latch of U.S. patent application Ser. No. 12/402,768 entitled "Latch Mechanism" (U.S. Patent Publication No. 2010/0235058), now U.S. Pat. No. 8,573,657 the entire contents of each of these applications being incorporated herein by reference. Powered latch 16 has locked and unlocked states corresponding to manual door locks. Switch or sensor 15 is typically included in handle assembly 10 if handle assembly 10 does not include a Passive Entry Passive Start system (PEPS). A PEPS system typically includes a fob that can be detected by an antenna in the vehicle. The PEPS controller unlocks the vehicle door(s) if it senses an authorized fob, and locks the doors after the fob/user is inside the vehicle. Because the vehicle is locked/unlocked based on detection of an authorized fob, no pushbuttons or other specific manual input by a user is required for operation or a PEPS system.

In vehicles that are not equipped with a PEPS system, a user pushbutton 15 or other suitable input (e.g. remote fob with pushbutton lock/unlock feature) is utilized. A sensor symbol or indicia 15A may be provided to enable a user to locate the sensor 15. Indicia 15A may comprise lines that are printed on outer surface 11, or the sensor symbol 15 may comprise side-by-side raised ridges and grooves that form lines, a pad lock icon, or the like. Sensor 15 may comprise a push button that unlocks the vehicle doors in substantially the same manner as known remote pushbutton fobs/powered door locks. The surface of indicia 15A may comprise a membrane or the like to permit manual switch activation. Still further, the sensor symbol/indicia 15 could include an LED light or the like that illuminates when the presence of a specific key fob (not shown) is detected and a user touches this area of surface 11. The handle assembly 10 may further include an illuminated lock symbol 15B that lights up when the vehicle is locked, and may be configured to fade to a non-illuminated state after a predefined time period (e.g. 5, 10, or 30 seconds, or a predefined number of minutes).

Instead of a pushbutton, sensor 15 may comprise a proximity locking sensor 44 (see also FIGS. 4-6) on the back side of indicia 15 that allows a user to lock the vehicle without using the key fob by moving his/her hand into a predefined detection range. An unlatch sensor 46 may be located on the backside of the handle class A surface and it may extend along a majority of the grip length of the handle adjacent edge 33 which the user activates via proximity or touch. Once the key fob presence is detected (range is 1 m) the vehicle owner is authenticated by the vehicle's keyless entry module via the established communication protocol between the vehicle owner's key fob, via an LF antenna 18 packaged inside the module housing 36 facing the outer

surface of the handle (i.e. behind the class A surface), the DCU and the BCM body control module.

In summary, there are typically at least three electrical elements included in the entry system: 1) a proximity or touch lock sensor 44; 2) a proximity or touch unlatch sensor 46; 3) a LF Antenna. Front and rear door handle 10 and 10A, respectively, may have the same number of electrical elements or fewer depending on the level of keyless entry functionality the OEM intends to offer to the Customer.

The surface 18 may comprise an antenna that is operably connected to a low frequency receiver to thereby determine if a specific key fob is within a predefined distance. A piezoelectric touch sensor or capacitive (i.e. proximity) unlatch sensor 46 may be positioned behind the antenna layer 18. A series of numbers of other indicia may be utilized to form the keypad 20. Keypad 20 can be actuated by a user touching the surface 11 in the region of the indicia 20. In the illustrated example, the indicia forming hidden keypad 20 comprise numbers that are visible only when lit. For example, each number may comprise a lens or aperture having the shape of the number, and an LED or other light source may be positioned behind the aperture. When the handle assembly 10 detects the presence of a user as a result of a key fob being present and as a result of touching surface 11, the LEDs may light up, thereby causing the indicia 20 to illuminate and become visible. The hidden keypad 20 permits a user to enter a specified code to thereby authorize entry. A chrome strip 22 or the like may extend vertically to visually divide the surface 11 and provide a distinctive appearance.

Referring again to FIG. 3, recess 12 may comprise a shallow inwardly depressed curved concave surface 23 of upwardly extending portion 7 of doorframe 6 that forms a pocket for receiving a user's fingers. Alternately, the outer surface may comprise an outwardly-protruding surface 11A having inner surface 24A. If handle 10 includes an outwardly-protruding surface 11A, surface 23 may be shallow, or flush with outer surface 8. The module 14 may extend inwardly to cover a portion of recess 12 and form an inwardly facing surface 24. Surfaces 23 and 24 intersect at inner corner 25. The handle is positioned at an ergonomic location on the door 2, 3 such that it is convenient for a user to touch the handle surface 11 and unlatch the door 2, 3 and then use their fingers to grab the door 2, 3 via the pocket or recess 12 described earlier to control the door 2, 3. The concave surface 23 may be partially or completely formed in the front pillar structure of rear door 3, or it may be formed in an outer surface (e.g. surface 5) of the door. Thus, edge 33 and inner surface 24 may be formed by the vehicle door and the concave, outwardly opening portion 23 may be formed by the vehicle body.

With further reference to FIG. 4, handle assembly 10 includes a module housing 36 disposed in an opening 114 defined by edge 118 of appliqué 7. Module housing 36 is formed by outer and inner members 104 and 106, respectively (see also FIG. 5), which members may comprise a molded polymer material. Module housing 36 is secured to inner door structure 92 by conventional screws or threaded fasteners 94 and nuts 96. Threaded fasteners 94 extend through openings 98 in flange(s) 102 of inner member 106. Flanges or tabs 108 of outer member 104 are received in channels 120 (FIG. 5) formed in sidewalls 110 of inner member 106. Screws 112 or other suitable fastening arrangement interconnect outer and inner members 104 and 106, respectively. Flanges/tabs 108 may comprise barbed members, and channels 120 may comprise corresponding snap fit connectors. Barbed connectors of this general type are

well-known, and the details of the connection of tabs **18** and channels **120** will therefore not be described in detail herein. Outer and inner members **104** and **106**, respectively, together define an interior space **115**. When fully assembled, keyless entry module **14** (FIGS. 6 and 7) is disposed in space **115**. A finger access pocket **117** (FIG. 4) is formed/molded integrally into the appliqu  7.

When layer **26** and housing **28** are assembled, a module housing **36** is formed. In the illustrated example, the housing **36** has a quadrilateral perimeter shape **38** when viewed from the front (FIG. 6), and it also has a quadrilateral perimeter shape **40** in edge view (FIG. 7). It will be understood that the shape and size of the perimeters **38** and **40** may be configured as required for a particular application. With reference to FIGS. 6 and 7, keyless entry module or subassembly **14** has a six-sided housing **136**. A transverse interior wall **41** divides the interior space of housing **136** into a first compartment or space **42** and a second compartment or space **43**. The sidewalls of the module housing **36** have thicknesses "W1," "W2," "W3," "W4," and "W5." Housing **136** may comprise a polymer or other suitable material. Lock sensor **44** is disposed in space or cavity **42**. The lock sensor **44** may be a piezoelectric (touch) or capacitive (i.e. proximity) sensor. As discussed in more detail below, after closing vehicle door **2**, a user actuates lock switch/sensor **44** to cause the latch **16** to shift to a locked configuration. This may be done by touch if sensor **44** is a touch-sensitive switch, or by moving a hand into the vicinity of sensor **44**. As shown in FIG. 7, the antenna **18** may be disposed on an inner side of the layer of material **26** within cavity or space **43** such that antenna **18** faces outwardly when handle **10** is fully assembled to a vehicle door **2**. Unlatch sensor **46** comprises a piezoelectric or capacitive sensor that is disposed on a sidewall **48** of housing **36**. Sensor **46** determines if a user has touched module **14**, or is within a predefined distance of module **14**, to thereby unlatch powered latch **16**.

The module **14** may include one or more LED lights **47** or a light pipe (FIGS. 6, 7) that are configured to illuminate the keypad numbers and also finger access pocket outer surface **12**. The LED light for pocket illumination faces inward towards pocket **12** whereas the LED lights for keypad numbers face outward towards surface **26**. Surface **26** comprises a clear plastic that is painted black and laser etched to form the keypad numbers/openings adjacent to antenna layer **18** to permit light from an internally mounted LED light source **47**. LED light source **47** is positioned such that it does not interfere with the function or package space of the antenna and illuminates the outer layer **26**. Outer layer **26** may comprise a light-transmitting material (clear plastic can be painted black and the illumination area laser etched) for a particular application. The pocket **12** also can be illuminated to guide the user to the area where to place his/her fingers. For example, an LED **47** may be configured to light up if the system senses an authorized keyless fob in the vicinity, or if a correct security code has been entered utilizing the hidden keypad **20**. Also, an LED **47** may light up when powered latch **16** shifts to an unlatched state. The LEDs **47** may have different colors to signify a "positive" result (e.g. an authorization code has been recognized by the system), and a different color (e.g. red) may be utilized to indicate that a "negative" outcome has occurred (e.g. the system determines that an incorrect authorization code has been entered utilizing the hidden keypad **20**).

In use, if powered latch **16** is in a locked configuration, and a user approaches the vehicle **1**, antenna **18** detects if the user has a keyless entry fob having a security code that is recognized by the system. If the system (e.g. keyless entry/

door controller module **13**) detects an authorized security code, the user is then authenticated, and the controller module **13** is in an "authenticated" state. If a user has been authorized, the user can then place his or her hand (or other object) within a predefined distance of sensor **46** (if sensor **46** comprises a capacitive sensor), and controller module **13** will generate a signal to the powered latch **16**, which causes the latch **16** to shift to an unlatched configuration. Alternatively, if sensor **46** comprises a piezoelectric or other touch sensor, a user can touch the back side surface **24** of module **14**, and controller module **13** will then generate a signal causing powered latch **16** to shift to an unlatched configuration. Still further, the system may utilize a security code that is entered utilizing the hidden keyboard **20**. The system may be configured to require a key fob for authenticating the vehicle owner.

After the powered latch **16** shifts to the unlatched position, a user may insert his or her fingers into outwardly facing recess **12** (FIGS. 2 and 3), and curl the ends of his or her fingers around edge **33** to contact inwardly facing surface **24**. A user then pulls the door **2** to an open position. When a user closes the door, it may be closed initially in a conventional manner by swinging the door shut. This causes the powered latch **16** to shift to a latched configuration, holding the door **2** in a closed position. If a user desires to lock the door from the outside, he or she actuates sensor **44** (FIGS. 6 and 7) by touching the surface of module **14** adjacent the sensor symbol **15** (FIG. 5), or by bringing his or her hand sufficiently close to sensor **44** if sensor **44** comprises a capacitive sensor.

With further reference to FIGS. 8 and 9, a handle **150** according to another aspect of the present invention includes a polymer core member or element that is connected to edge **154** of sheet metal **156** utilizing hooks **158** or other suitable connector. Sheet metal **156** may be bent or formed inwardly to form a recess **166**. A portion **168** of recess **166** is in the form of a pocket formed by core element **152**. An appliqu  **7A** connects to core element or member **152** utilizing barbed connectors **162** or the like. Appliqu  **7A** and core member **152** together define a space **164**. A module **14A** that is substantially the same as module **14** is disposed in space **164**. Module **14A** is positioned such that antenna **18A** faces outwardly and sensor **46A** faces inwardly.

The flush handle assembly **10** described above in connection with FIGS. 1-9 eliminates the need for a movable, protruding handle assembly and associated components. This provides a more aesthetically pleasing appearance, reduces complexity, assembly labor, cost and improves vehicle aerodynamics and quality.

The flush handle assembly **10** has been shown and described mounted to an upwardly extending portion **7** of a door frame **6**. However, the handle assembly **10** may also be positioned in the lower portion of door **2** (FIG. 1) below beltway **3**. In general, the handle assembly **10** is positioned relatively close to the outer door edge **9** opposite front edge **17** of door **2** to thereby facilitate ergonomically pleasing opening/pivoting of the door by a user.

It is to be understood that variations and modifications can be made to the aforementioned structure without departing from the concepts of the present invention, and further it is to be understood that such concepts are intended to be covered by the following claims unless these claims by their language expressly state otherwise.

The invention claimed is:

1. A flush handle system for a vehicle, comprising:
a vehicle door defining inner and outer sides, the outer side having an outwardly facing flat outer surface, the outwardly facing flat outer surface defining an edge that extends around an opening in the flat outer surface;
a pocket formed in the vehicle door, wherein the pocket is connected to the opening;
an integrally formed handle that is immovable relative to the outer side of the vehicle door and extends over a portion of the pocket whereby a user can insert fingers through the opening into the pocket and pull outwardly to open the vehicle door without moving the handle portion relative to the vehicle door, and wherein the handle does not protrude outwardly beyond the flat outer surface of the outer side of the door; 15
an unlatch sensor mounted to the vehicle door and to generate a predefined signal in response to detect a hand of the user in the pocket at a predefined range of the unlatch sensor, wherein the unlatch sensor is selected from the group consisting of proximity sensors and touch sensors; 20
a proximity lock sensor selected from the group consisting of proximity sensors and touch sensors and to allow the user to lock the vehicle door without using a specific key fob by moving the user's hand into a predetermined range of the proximity lock sensor; 25
a powered latch defining locked and unlocked states and latched and unlatched configurations, wherein the powered latch retains the vehicle door in a closed position when the powered latch is in the latched configuration, and permits opening of the door when the powered latch is in the unlatched configuration; and
a low frequency (LF) antenna to detect the specific key fob of the user when the user is within a predefined distance of the vehicle to authenticate the user to move the powered latch into the unlocked state; 30
wherein the powered latch unlatches by shifting from the latched configuration to the unlatched configuration in response to the unlatch sensor generating the predefined signal and if the powered latch is in the unlocked state; 35
wherein the powered latch shifts from the unlocked state to the locked state in response to an actuation of the proximity lock sensor when the vehicle door is closed; 40
and
wherein the locked and unlocked states of the powered latch correspond to manual door locks.
2. The flush handle system of claim 1, wherein:
at least one of the predefined range of the unlatch sensor and the predetermined range of the proximity lock sensor is about 6-8 mm. 45
3. The flush handle system of claim 1, wherein: a visual indicator comprises the pocket formed in the outer surface of the vehicle door, wherein the visual indicator illuminates when at least one of the unlatch sensor and the proximity lock sensor determines that the user has actuated the at least one of the unlatch sensor and the proximity lock sensor. 50
4. The flush handle system of claim 1, wherein:
the powered latch includes a rotatable catch to engage a striker and retain the vehicle door in a closed position, and a movable pawl that selectively engages the rotatable catch and prevents rotation of the rotatable catch when the pawl is in an engaged position such that the latch is in the latched configuration, and wherein the pawl permits rotation of the rotatable catch when the pawl is in a disengaged position such that the powered latch is in the unlatched configuration. 55
5. The flush handle system of claim 1, wherein:
the powered latch includes a rotatable catch to engage a striker and retain the vehicle door in a closed position, and a movable pawl that selectively engages the rotatable catch and prevents rotation of the rotatable catch when the pawl is in an engaged position such that the latch is in the latched configuration, and wherein the pawl permits rotation of the rotatable catch when the pawl is in a disengaged position such that the powered latch is in the unlatched configuration. 60
6. The flush handle system of claim 1, wherein:
the powered latch includes a rotatable catch to engage a striker and retain the vehicle door in a closed position, and a movable pawl that selectively engages the rotatable catch and prevents rotation of the rotatable catch when the pawl is in an engaged position such that the latch is in the latched configuration, and wherein the pawl permits rotation of the rotatable catch when the pawl is in a disengaged position such that the powered latch is in the unlatched configuration. 65

latch is in the unlatched configuration, the powered latch further including an electrically-powered actuator that moves the movable pawl upon actuation of the electrically-powered actuator to latch and/or unlatch the powered latch.

5. A flush handle system for a vehicle, comprising:
a vehicle door defining inner and outer sides, the outer side having a flat outer surface;
a handle comprising an opening in the flat outer surface that leads to a pocket formed in the vehicle and extends over a portion of the pocket whereby a user can insert fingers into the pocket and pull outwardly to open the vehicle door without moving the handle relative to the vehicle door, wherein said handle is disposed inside of the flat outer surface of the outer side of the vehicle door;
an unlatch sensor mounted to the door adjacent the pocket at a location that is inside of the portion of the outer surface defining a surface contour and to generate a predefined signal in response to detect a hand of the user in the pocket at a predefined range of the unlatch sensor, wherein the unlatch sensor is selected from the group consisting of proximity sensors and touch sensors;
a proximity lock sensor selected from the group consisting of proximity sensors and touch sensors and to allow the user to lock the vehicle door without using a specific key fob by moving the user's hand into a predetermined range of the proximity lock sensor;
a powered latch defining locked and unlocked states and latched and unlatched configurations, wherein the powered latch retains the vehicle door in a closed position when the powered latch is in the latched configuration, and permits opening of the vehicle door when the powered latch is in the unlatched configuration; and
a low frequency (LF) antenna to detect the specific key fob of the user when the user is within a predefined distance of the vehicle to authenticate the user to move the powered latch into the unlocked state;
wherein the powered latch unlatches by shifting from the latched configuration to the unlatched configuration in response to the unlatch sensor generating the predefined signal and if the powered latch is in the unlocked state;
wherein the powered latch shifts from the unlocked state to the locked state in response to actuation of the proximity lock sensor when the vehicle door is closed;
wherein the locked and unlocked states of the powered latch correspond to manual door locks;
wherein the door includes a lower portion, a window above the lower portion, and beltline between the window and the lower portion of the door, and wherein the door includes an upright structure extending vertically along a side edge of the window; and
wherein the upright structure includes an outwardly facing outer side surface and an outwardly opening pocket, the upright structure further including a flange extending along at least one side of the pocket, the flange having an inner surface that faces generally opposite the outer side surface to form a handle, wherein the flange is rigidly fixed to the upright structure.

6. The flush handle system of claim 5, wherein:
a surface contour of the outer side surface of the upright structure over the flange is substantially identical to a surface contour of the outer side surface immediately adjacent the flange such that the appearance of the outer

9

side surface of the upright structure over the flange is substantially the same as the appearance of the outer side surface immediately adjacent the flange.

7. The flush handle system of claim 6, including:

a visual indicator adjacent the handle that illuminates when at least one of the unlatch sensor and the proximity lock sensor determines that the user has actuated the at least one of the unlatch sensor and the proximity lock sensor.

8. The flush handle system of claim 7, wherein: the vehicle door includes a thin layer of material having a generally planar portion covering the unlatch sensor.

9. The flush handle system of claim 8, wherein:

the thin layer of material extends over the flange and includes an edge extending along the distal edge of the flange.

10

10. The flush handle system of claim 8, wherein: the visual indicator comprises a plurality of parallel lines on the thin layer of material directly over the unlatch sensor.

5 11. The flush handle system of claim 7, wherein: the pocket has an oblong shape having a vertical dimension that is substantially greater than a horizontal dimension; the flange extends horizontally over a portion of the pocket and terminates at an elongated vertically extending distal edge.

12. The flush handle system of claim 11, wherein: the vertically extending distal edge is substantially linear, and wherein an opposite edge surface of the pocket has a concave curved shape whereby the pocket defines an elongated opening having opposite upper and lower ends.
